F. W. H. Attorney

UNITED STATES PATENT OFFICE

JOSEF PRINZ, OF DINSLAKEN, GERMANY

BOILER FOR HOT WATER AND LOW PRESSURE STEAM-HEATING

Application filed March 21, 1929, Serial No. 348,919, and in Germany February 7, 1929.

Boilers for hot water and low pressure steamheating are known in which smoke and water pockets are distributed alternately and uniformly from the boiler jacket over the 5 furnace, the water pockets being connected to the water jacket at the top and at the rear.

This invention differs advantageously from the known art in that the boiler jacket is made of U-shaped cross-section and that 10 the ends of the arms are connected by a non-water conducting wall which is removable or provided with a door; and further in that the water pockets extend continuously from the rear wall of the boiler over the entire 15 depth of the furnace and that the heating gases rise freely between the pockets and pass into the flue through a heating gas collecting chamber.

By removing the non-water-conducting 20 wall or opening the door in this wall the pockets are exposed, so that they can be easily cleaned also when the boiler is in use, whereby a good heat transmission is ensured, whereas, owing to the arrangement of the 25 pockets a favorable guiding of the water and smoke is obtained.

An embodiment of the invention is illustrated by way of example in the accompanying drawing in which:

30 Fig. 1 shows a vertical section through the middle of the boiler.

Fig. 2 is a section on line 2—2 of Fig. 1.

Fig. 3 is a cross-section on line 3—3 of Fig. 2.

35 The boiler of U-shaped cross-section consists of a rear boiler chamber wall 2 and side chamber walls 3 connected to an upper water chamber 1. Between the outer chambers 3 water pockets 4 are arranged uniformly distributed, and communicate with the water 40 chambers 1 and 2. The hollow grate bars are inclined and hollow throughout their whole length. These bars are in direct communication with the water chamber 2 and with the side water chambers 3 through a transverse tube 6. The smoke flues 7 formed by the water pockets 4 are covered by distributing plates 8 so that the heating gases 45 pass in the direction of the arrow C around the distributing plates 8 to flow into the col-

lecting chamber 9 and then to the discharging pipe 11 provided with a throttle valve 10. The flue gas collecting chamber 9 is situated along its whole length in the water jacket 12 which has connecting flanges 13 for the heating surface, whereas the heating gases are returned through the tubular connection 14. The ends of the water chamber 3 are, according to the invention, interconnected by a non-water-conducting wall 55 which is either removable or provided with a door 17. A fire door 15 and an ash pit drop door 16 are also arranged in the front wall of this boiler. By removing this water conducting wall or opening the door 17 the 60 heating gas flues are easily accessible for cleaning. The flue gas collecting chamber 9 is also provided with a removable cover 18 for the same purpose. When used as boiler for a hot water heating installation the boiler 65 has a thermometer 19 whereas when used as low-pressure steam boiler the necessary fitting, such as water gauge and manometer are provided, in which case the chamber 12 serves as steam collector. 75

I claim:—

1. A boiler for hot water and low pressure steam heating installations, comprising in combination a water jacket substantially U-shaped in transverse cross section closed 80 at its top by a water and steam chamber, a plurality of spaced water pockets depending from said chamber and extending parallel with the arms of the U-shaped jacket, said pockets being in communication with the jacket at the rear, a furnace between the arms of the jacket and below said pockets, an off-take flue arranged in said chamber and connected to the tops of the spaces between the 85 pockets, and readily removable means closing the open side of the U-shaped jacket. 90

2. A boiler construction as in claim 1, wherein the removable means comprises a door co-extensive with the pockets permitting 95 cleaning of the spaces therebetween.

In testimony whereof I affix my signature.
JOSEF PRINZ.
